UNITED STATES PATENT OFFICE.

CADE BETHEA, OF MOBILE, TEXAS.

BED-STAY.

SPECIFICATION forming part of Letters Patent No. 390,336, dated October 2, 1888.

Application filed January 20, 1888. Serial No. 261,341. (No model.)

To all whom it may concern:

Be it known that I, CADE BETHEA, of Mobile, in the county of Tyler and State of Texas, have invented a new and Improved Bed-Stay, 5 of which the following is a full, clear, and exact description.

My invention relates to stays for bedsteads, to brace them against racking strains, and has for its object to provide a simple, inexpensive, and efficient device of this character which is an improvement on the bed-stay for which United States Letters Patent No. 374,443 were granted to me December 6, 1887.

The invention consists in certain novel features of construction of the bed-stay, all as hereinafter described and claimed.

Reference is to be had to the accompanying drawings, forming a part of this specification, in which similar letters of reference indicate 20 corresponding parts in both the figures.

Figure 1 is a plan view of a bedstead with some of the mattress-supporting slats broken away and with my improved stay applied; and Fig. 2 is a perspective view of the center 25 coupling and lock of the bed-stay, drawn to an enlarged scale.

In carrying out the present invention I use two main stay-wires, A B, which are doubled at their center parts, and are twisted a turn 3c or two at *a b*, respectively, to form a long loop, A', in the stay-wire A and a shorter loop, B', in the stay-wire B. From its loop A' the wire A is diverged toward the head-board C and side rails, D D, of the bedstead, 35 and after being passed through eyes or staples E E, fixed in the opposite rails, D D, the extremities of said wire A are connected to hooks, eyes, or staples F F, fixed in the head-board of the bedstead. The stay-wire fastenings E F are arranged about like distances 40 from the adjacent corner-posts G G of the bedstead. From its loop B' the stay-wire B is diverged toward the foot-board H and side rails, D D, of the bedstead, and after being 45 passed through eyes or staples I I, fixed in the opposite rails, D D, the extremities of the wire B are attached to eyes or staples J J, fixed in the foot-board of the bedstead, said parts I J being arranged about like distances

from the adjacent corner-posts K K of the 5c bedstead.

As a locking device for the bed-stay, I employ a plate or lever, L, which is fulcrumed on the end of the long loop A' of the stay-wire A, and is provided with a laterally-bent hook 55 or lip, M, at its opposite end, and in one edge has one or more notches, *l*, three being preferred, and whereby, when the end of the loop B' of the stay-wire is slipped into one of the notches while the lever L stands about vertically, and the lever is then swung downward until its hook M may be caught under one side of the stay-loop A', as shown in the drawings, the opposite stay-wires A B will be drawn or strained up tightly, and the wires 65 will not only hold the corner-posts firmly to the head and foot boards and opposite side rails of the bedstead, but the wires will also draw the side rails, D D, tightly to the ends of the bed-slats N, thus making of the bedstead a 70 very firm and substantial structure, strongly braced against racking strains.

The locking-lever L is made and operates substantially in the manner described for the locking device in my aforesaid prior patent; 75 but the blocks on the stay-wires shown in said patent are herein substituted by the bends or twists *a b* of the stay-wires, which is a far simpler and more inexpensive construction, while the connection of the extremities of the 80 stay-wires with both the side rails and the head and foot boards of the bedstead, as herein described, instead of to the corner-posts of the bedstead, as in the former construction, costs but very little more, while greatly increasing 85 the stability of the entire structure.

Having thus described my invention, what I claim as new, and desire to secure by Letters Patent, is—

1. A bed-stay consisting of wires A B, doubled at their center parts and twisted at *a b*, to form loops A' B', respectively, and diverged from said twisted parts *a b* and attached to the corner portions of the bedstead, and a tension and locking device consisting of a straining-lever fulcrumed to one of the loops and adapted to lock thereon and engaging the other loop, substantially as herein set forth. 90 95

2. The combination, in a bed-stay, of wires A B, bent double and twisted at *a b*, to form loops A'B', respectively, and the diverging end parts of said wires A B, passed through eyes 5 or staples E I in the bedstead side rails and connected to the head and foot boards of the bedstead, and a tension and locking device, L,

having a hook, M, and notches *l* and engaging the wire loops A'B', substantially as described, for the purposes set forth.

CADE BETHEA.
